Arthur J. Malavazos, Oakland, Calif., assignor to Friden Calculating Machine Co., Inc., a corporation of California

Application July 20, 1954, Serial No. 444,477

12 Claims. (Cl. 235—145)

This invention relates to calculating machine keyboards and more particularly to full keyboards of the character used in portable calculating machines such as those manufactured by the Friden Calculating Machine Company of San Leandro, California.

It is among the objects of the invention to provide an improved calculating machine keyboard which has a much lighter and more uniform key action than corresponding keyboards currently in use; which has means accurately guiding the keys in their value selecting movements and, at the same time, permits a loose fit between the key stems and the key carrying frame so that the frame and key stems do not have to be manufactured with the high degree of accuracy presently required; which utilizes flat key stems so arranged that the operating pressures are between the flat sides of the key stems and the keyboard frame thereby reducing wear of the stems and frame to an entirely negligible amount; which provides means for locking and releasing the key rows individually by operation of the corresponding "0" keys, and control means for locking and releasing the entire keyboard; and which provides a construction that is simple and economical to manufacture and assemble and easy to service when necessary.

Other objects and advantages will become apparent from a consideration of the following description and the appended claims in conjunction with the accompanying drawings wherein:

Fig. 1 is a fragmentary top plan view of a keyboard illustrative of the invention, parts being broken away and shown in cross-section to better illustrate the construction thereof;

Fig. 2 is a longitudinal cross-sectional view on the line 2—2 of Fig. 1;

Fig. 3 is a fragmentary, transverse cross-sectional view on the line 3—3 of Fig. 2; and

Fig. 4 is a fragmentary, transverse cross-sectional view on the line 4—4 of Fig. 2.

With continued reference to the drawings, the numeral 10 generally indicates the keyboard frame, the numeral 11 generally indicates a plurality of digit keys mounted in the frame for manual operation, and the numeral 12 generally indicates "0" keys disposed in a row across the front portion of the keyboard frame.

The frame 10 comprises a flat upper plate 14 of rectangular shape having key stem receiving apertures 15 of elongated, rectangular shape provided therein and disposed in ordinarily arranged rows extending longitudinally of the frame plate, the apertures being uniformly spaced along the corresponding rows and having their major dimensions extending along the rows. The frame also comprises a flat, lower or bottom plate 16 also of rectangular shape having at its front end an upwardly offset flange portion 17 parallel to the front portion of the upper or top plate 14, said lower plate having elongated apertures 18 therein each in registry with a corresponding aperture in the top plate 14. The plates 14 and 16

2

are secured in spaced-apart and parallel relationship to each other by a spacing plate 20 extending transversely of the frame between and perpendicular to the plates 14 and 16 near the front end of the frame and rigidly secured at its edges to the top and bottom frame plates and a similar spacing plate 21 extending transversely of the frame between the plates 14 and 16 near the rear end of the frame. An additional plate 22 is also disposed between the rear ends of the frame plates 14 and 16 to hold these plates in spaced-apart and parallel relationship, the plates 20 and 22 having notches, as indicated at 23 for the plate 20, extending downwardly from the upper edge thereof at locations spaced apart therealong, and other spacing and fastening means may be used to further reinforce the connection between the plates 14 and 16, if desired.

Each of the digit keys 11 comprises an elongated, flat stem 24 extending through registering apertures 15 and 18 in the frame plates 14 and 16 and having straight and substantially parallel edges and its major cross-sectional dimension extending along the corresponding key row, a head or block 25 secured on the upper end of the stem 24 in spaced relationship to the upper surface of the top frame plate 14 and a pin 26 projecting perpendicularly from the stem near the lower end thereof and below the bottom frame plate 16. A compression spring 28 surrounds each key stem 24 between the top plate 14 and the bottom end of the corresponding key head 25 to raise the keys and, when a key is in raised position the pin 26 projecting perpendicularly from the lower end portion thereof bears against the under surface of the bottom frame plate 16 to limit upward movement of the key, the bottom surface of the plate 16 preferably being provided with strips of sound-deadening sheet material which the pins engage so that the keys will not make a noise as they are raised to their upper limiting position.

At a location spaced below the corresponding head 25 each key is provided intermediate the width of one of the flat sides thereof with a detent formation 30 projecting from the flat side of the key. These detent formations may be conveniently formed by pressing a portion of the key stem outwardly at one side of the key with a consequent depression of the material at the opposite side of the key stem and the formations all project from the same sides of the key stems in each key row and preferably from the same sides of the stems in all of the rows. As is best shown in Fig. 3, each detent formation 30 has a flat top end 31 disposed in a plane substantially perpendicular to the longitudinal center line of the key stem, a downwardly and inwardly inclined cam surface 32 at its lower end and a somewhat convex outer side having a bulge, as indicated at 33, immediately above the upper, outer end of the cam surface 32 on the lower end of the formation. Each key stem is also preferably provided with an aperture 35 of rectangular shape extending upwardly from the upper end of the corresponding detent formation 30 medially of the width of the key stem.

A plurality of bails 38 extend longitudinally of the keyboard frame 10 between the frame plates 14 and 16 one along each row of key stems 24 and at the sides of the stems of the corresponding row from which the detent formations 30 project. Each of the bails 38 comprises a flat cross-member 40 of substantially rectangular shape, rounded legs 41 and 42 projecting perpendicularly from the member 40 one at each end thereof, an extension 43 of the member 40 extending rearwardly beyond the bail leg 42, and a flange 44 projecting perpendicularly toward the key stems of the corresponding key row from the edge of the member 40 remote from the edge of this member nearest the legs 41 and 42.

and lower frame plate 16. Pivot pins 46 and 47 project outwardly from the legs 41 and 42, respectively, coaxially of each other and through apertures in the front and rear frame spacing plates 20 and 21 near the bottom frame plate 16, and the flange 44 is disposed near the under surface of the top frame plate 14 in position to engage over the upper ends of the key stem detent formations 30 when the keys are depressed. Arms 48 and 49 project perpendicularly from the outer edge of each bail flange 44 in a direction away from the corresponding cross-member 40 of the bail and each arm 48 and 49 is provided at its outer end with an upwardly extending lug formation, as indicated at 50 and 51, extending through corresponding apertures 52 in the top plate 14, the arms 48 being disposed near the forward ends and the arms 49 near the rearward ends of the corresponding bails. Additional arms 36 project perpendicularly, one from each bail flange between the corresponding arms 48 and 49 and springs 37 are connected one between each arm 36, at the outer end thereof, and the frame plate 16 and resiliently rock the corresponding bails in a direction to bring the outer edges of the bail flanges into position to engage the detent formations 30 on the key stems of any depressed digit keys.

Each of the "0" keys 12 has a flat stem 54 slidably mounted in registering apertures in the upper and lower frame plates 14 and 16 and each of these stems carries on its upper end a key head 55 having a recess in its forward side so that the "0" keys can be manually raised above their normal position or manually depressed. A compression spring 56 surrounds each "0" key stem 54 between the top plate 14 and the bottom end of the key hand 55 to resiliently urge the "0" keys upwardly to their normal raised position.

Each bail is rocked to release any depressed digit key in the corresponding key row when the "0" key at the end of the same row is manually depressed. In order to accomplish this action the front leg 41 of each bail 40 is provided with a straight cam edge 58, inclined upwardly and toward the upper edge of the bail strip, and each "0" key stem has a rearwardly projecting extension or arm 59 which engages the cam edge 58 on the adjacent leg of the corresponding bail and rocks the bail in a direction to move the bail flange 48 away from the key stems when the "0" key is depressed.

A plurality of bellcrank levers 60 are disposed between the frame plates 14 and 16 each adjacent the side of a corresponding "0" key stem and each bellcrank lever is pivotally mounted at its angle on the associated "0" key stem 54 by a headed pin 61 extending perpendicularly from the "0" key stem and through the corresponding bellcrank lever. Each bellcrank lever bears at its upper end against the underside of the top frame plate 14 just forwardly of the associated "0" key stem and bears at its rearward edge below the pivot pin 61 against the front end of the pivot pin 46 of the corresponding latch bail 40. With this arrangement, whenever a "0" key is raised above its normal "up" position, the associated bellcrank lever 60 is rocked about its pivot pin 61 and bears against the bail pivot pin 46 with which it is engaged to force the corresponding bail rearwardly. Each of the apertures 52 in the top frame plate 14 has a rearward portion substantially equal to the width of the corresponding lug formation 50 and a forward portion wider than the rearward portion by an amount sufficient to permit rocking movement of the corresponding bail for latching and unlatching the detent formations on the corresponding digit keys, the wider portion of each aperture 52 being joined to the narrower portion thereof by an inclined cam shoulder 62. When a bail is forced rearwardly the lugs 50 and 51 thereon are forced into the narrow rearward portions of the corresponding apertures 52 and the bail is thereby locked against rocking movement in position to latch down any depressed digit key and lock against depression any raised key in the corresponding row of

keys. The depressed key in any row can thus be locked in latched-down position by merely raising above its normal "up" or raised position, the "0" key at the front end of the same row of keys.

5 A tension spring 64 connected between each bellcrank 60 immediately above the corresponding pivot pin 61 and the spacer plate 20 resiliently urges each bellcrank lever to rock in a direction to release the associated bail for forward movement when the "0" key is returned to its normal position.

When a depressed "0" key is released, rocking movement of the associated bellcrank lever 60 by spring 64 is terminated by engagement of the front edge of the bellcrank lever with a stop pin 63 carried by the key stem 54 below the pivot pin 61.

A flat spring 65 is secured between the rear spacer plate 22 and an upwardly directed flange 66 extending across the rearward end of the bottom frame plate 16 and this spring is provided with a plurality of spring fingers 67

20 each of which bears against the rearward end of the rearward extension 43 of a corresponding bail 40 and resiliently urges the bail in a forward direction, any bail that has been locked by raising of the corresponding "0" key being moved forwardly to its released position upon return of the "0" key to normal position.

Suitable means are also provided for simultaneously locking all of the latch-down bails in key-latching position and this means, as illustrated, comprises a bail, generally indicated at 68, having a crossbar 69 extending through

30 registering apertures 70 in the latch-down bails 40 and connected by legs, as indicated at 71, extending one from each end of the crossbar 69, to a rock shaft 72 which extends transversely of the keyboard between the lower edges of the latch-down bails 40 and the bottom frame

35 plate 16 of the keyboard frame. The apertures 70 are elongated longitudinally of the latch-down bails 40 and the bail crossbar 69 is normally at the rear ends of these apertures so that the bails 40 can be individually moved rearwardly by raising of the corresponding "0" keys 12,

40 as explained above, and will be collectively moved rearwardly when the bail 68 is rocked in a rearward direction or in a clockwise direction, as viewed in Fig. 2. When the bail 68 is released the spring fingers 67 will return all of the latch-down bails 40 forwardly from their locked position.

Suitable means are also provided for simultaneously moving all of the latch-down bails 40 away from their key-latching position to release all of the depressed keys of the keyboard when it is desired to completely clear

50 the keyboard and this means comprises a flat bar 74 extending through registering aperture 75 of substantially square shape in the latch-down bails 40 near the front ends of these bails. The bar 74 is provided at locations spaced apart along its upper edge with upwardly projecting abutment formations 76 each of which engages the portion of the associated latch-down bail 40 between the upper edge of the corresponding aperture 75 and the bail flange 44 so that, when the bar 74 is moved to the right,

55 as viewed in Fig. 3, all of the latch-down bails 40 will be rocked to release any keys held in latched-down position by the bails. Both manually operated and machine operated mechanisms may be provided to move the bar 74 so that the keys can be released at the will of the operator and will be automatically released at the termination of

60 a calculating operation of the associated calculating machine.

A pair of selection bars, as indicated at 77 and 78, are disposed in substantially vertical position below each row of digit keys 11 and each of these selection bars is 70 provided in its upper edge with cam notches, as indicated at 80 for the bar 77 and 81 for the bar 78, which are engaged by the pins 26 of the corresponding digit keys to differentially shift the bars 77 and 78 forwardly to condition the actuating mechanism of the calculating machine to enter selected values in the machine register, in

a manner well known to the art. The bar 77 is supported near its front and rear ends for longitudinal movement on upwardly extending pivoted links 82 and 83 and the bar 78 is similarly supported on upstanding pivoted links 84 and 85. The bar 77 is disposed at the left-hand side of the bottom ends of the corresponding row of key stems 24 and is actuated by the keys numbered from "1" to "5" of the corresponding key row, the pins 26 carried by these key stems extending to the left from the lower end portions of the associated key stems, and the bar 78 is positioned at the right-hand side of the same row of key stems and is actuated by the "6" to "9" keys, inclusive, of the corresponding key row, the pins 26 carried by these keys projecting to the right from the lower end portions of the corresponding key stems.

A guide plate 86 is disposed at one side of each pair of selection bars 77 and 78 and each such guide plate is of elongated, rectangular shape and is rigidly supported at its front and rear ends by a front transverse frame member 87 and a rear transverse frame member 88, these transverse frame members constituting a portion of the machine frame and extending transversely of the machine in parallel and spaced-apart relationship to each other below the keyboard of the machine.

Each guide plate 86 is provided with a substantially straight upper edge positioned immediately below the bottom surface of the lower frame plate 16 of the keyboard and is also provided with notches 90 of rectangular shape extending downwardly from the top edge thereof at locations spaced apart along the guide bar to respectively receive the pins 26 projecting from the lower end portions of the key stems of the adjacent rows of keys. Each notch 90 has a length transversely of the corresponding guide plate sufficient to permit free up-and-down movement of the corresponding digit keys as these keys are manually depressed and released and has a width substantially equal to the diameter of the pins 26, the guide notches providing just sufficient clearance for free movement of the pins therethrough. At its upper end each notch is flared outwardly, as indicated at 91, to guide the corresponding pins into the upper ends of the notches when the keyboard is being assembled with the machine, the pins being rigidly held to straight line movements after they have entered the notches and the guide plates being effective to take up the reaction between the pins and the corresponding selection bars 77 and 78 as downward movements of the pins moves the selection bars forwardly against the spring resistance.

With this arrangement, it is not necessary to maintain any close fit or tolerance between the side edges of the key stems and the apertures in the plates 14 and 16 through which the key stems extend and there is no wear between the edges of the key stems and the ends of the key stem receiving notches since no pressure is applied between these surfaces. Also, with the rockable latch-down bails 40, it is not necessary to maintain a close fit between the sides of the key stems and the sides of the key stem receiving apertures in the keyboard frame plates and no appreciable wear occurs between the sides of the key stems and the longitudinal edges of the frame plate apertures since the areas involved are relatively large and there is no definite pressure which would tend to cause wear. There is also no appreciable wear between the pins 26 and the sides of the notches 90 in the guide plates 86 since the pins are of smooth, cylindrical shape and are hardened and the sides of the notches 90 may be made entirely smooth and the guide plates may also be hardened to minimize wear. If, after a long period of service, sufficient wear should occur in the notches 90 to affect the operation of the keys, it would be a simple matter to replace the guide bars 86, retaining the same keyboard in the machine.

By the use of the rockable latch-down bails 40 and the laterally projecting latch detents on the key stems the action of the keys is made uniform and extremely light,

wear between the key stems and the keyboard frame is substantially eliminated and accurate fitting of the key stems to the key stem receiving apertures in the keyboard frame is rendered unnecessary. By providing for longitudinal shifting movement of the bails the depressed key in any row can be locked in latched-down position by raising the corresponding "0" key and all of the depressed keys of the keyboard can be locked in latched-down position by rocking bail 68 in the proper direction. With the latch-down bails 40 unlocked, any depressed key is released to return to its upper position by depression of another key in the same key row, all latch-down keys being manually releasable by partial depression of other keys in the same key row, and all of the latch-down keys of the keyboard can be simultaneously released by operation of the release bar 74. By taking up the reaction between the selection bars and the actuating pins of the keys by the guide plates 86, wear between the key stems and the key stem supporting frame incident to the pressure necessary to move the selection bars is also eliminated.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A calculating machine keyboard comprising a frame having spaced-apart upper and lower plates provided with key stem receiving apertures, digit keys disposed in ordinarily arranged rows extending longitudinally of said frame and each comprising a flat stem extending slidably through said frame plates with its major transverse dimension extending along the corresponding key row, a head on one end of said stem in spaced relationship to the outer side of said upper plate, a key raising compression spring disposed between said upper plate and said key head, a pin projecting perpendicularly from the other end of said stem and movable away from and toward the outer surface of said lower plate, and a detent formation projecting from one side of said stem between said plates, bails extending longitudinally of said frame between said plates and one along each key row and each pivotally connected at its lower edge to said frame adjacent to said lower plate and having an offset flange extending along its upper edge for movement toward and away from the key stems of the corresponding key row for engaging the stem detent formations of depressed keys of the corresponding key row, and spring means connected between said frame and said bails resiliently urging said bails in their detent engaging direction.

2. A calculating machine keyboard comprising a frame having spaced-apart upper and lower plates provided with key stem receiving apertures, flat key stems slidably mounted in said plates for longitudinal movement and disposed in ordinarily arranged rows with the major transverse dimensions of each stem extending along the corresponding row, each key stem having a detent formation projecting from one side thereof, bails disposed between said plates and extending one along each row of key stems at the sides of said stems from which said detent formations project, each of said bails being pivoted to said frame adjacent said lower plate and having a longitudinally extending flange engageable with the detent formation on the stem of any depressed key in the corresponding row to hold the key in latched-down position, and spring means connected between each bail and the frame resiliently urging each bail in its detent engaging direction.

3. A calculating machine keyboard comprising a frame, digit keys disposed in ordinarily arranged rows extending

longitudinally of said frame and each including a flat key stem extending through and slidably mounted for longitudinal movement in said frame with its major transverse dimension extending along the corresponding row and provided with a detent formation projecting from one side thereof within said frame, bails extending longitudinally of said key rows within said frame and each pivotally connected to said frame for rocking movement into and out of engagement with the detent formations on the key stems of the corresponding key row, spring means connected between said bails and said frame resiliently urging said bails into engagement with the detent formations on the stems of any depressed keys in the corresponding rows, "0" keys disposed one at one end of each ordinal row of digit keys and each having a stem mounted for longitudinal movement in said frame, a cam formation on the end of each bail adjacent the corresponding "0" key stem, and an extension on each "0" key stem engaging the cam formation on the corresponding bail and effective to move the corresponding bail against the force of said spring means to release any latched-down digit key in the corresponding key row when a "0" key is depressed.

4. A calculating machine keyboard comprising a frame including spaced-apart and substantially parallel plates having key stem receiving apertures therein, digit keys disposed in ordinarily arranged rows and each having a flat key stem extending slidably through said frame, each key stem having its major transverse dimension extending along the corresponding row and having a latching detent projecting from one side thereof, key-latching bails extending one along each row of key stems between said plates and adapted to engage detent formations on key stems in the corresponding rows to latch depressed keys in depressed position, spring means connected between said bails and said frame resiliently urging said bails in their key-latching direction, one of said frame plates having apertures therein tapering in width from one end to the other and each of said bails having a lug formation received in a corresponding tapered aperture in said one frame plate and effective when at the narrow end of the corresponding aperture to hold the associated bail in key-latching position and when at the wide end of the corresponding aperture to free the associated bail for movement out of key-latching position, "0" keys disposed one at one end of each row of digit keys and each having a stem extending slidably through said frame, means acting between each "0" key stem and the corresponding bail to move the bail to key releasing position when the "0" key is depressed, and means acting between each "0" key and the corresponding bail to move the bail longitudinally and bring the lug formation thereof into the narrow end of the corresponding lug receiving aperture in said one frame plate when the "0" key is manually raised to thereby lock the associated key-latching bail in key-latching position.

5. A calculating machine keyboard comprising a frame including spaced-apart and substantially parallel plates having key stem receiving apertures therein, digit keys disposed in ordinarily arranged rows and each having a flat key stem extending slidably through said frame, each key stem having its major transverse dimension extending along the corresponding row and having a latching detent projecting from one side thereof, key-latching bails extending one along each row of key stems between said plates and adapted to engage detent formations on key stems in the corresponding rows to latch depressed keys in depressed position, spring means connected between said bails and said frame resiliently urging said bails in their key-latching direction, one of said frame plates having apertures therein tapering in width from one end to the other and each of said bails having at least one lug formation received in a corresponding tapered aperture in said one frame plate and effective when at the narrow

end of the corresponding aperture to lock the associated bail in key-latching position and when at the wide end of the corresponding aperture to free the associated bail for movement out of key-latching position, "0" keys disposed one at one end of each row of digit keys and each having a stem extending slidably through said frame, means acting between each "0" key stem and the corresponding key-latching bail to move the bail to key releasing position when the "0" key is depressed, means

10 acting between each "0" key and the corresponding key-latching bail to move the bail longitudinally and bring the lug formation thereon into the narrow end of the corresponding lug receiving aperture in said one frame plate when the "0" key is manually raised, a rockable bail extending transversely of said frame and engaging said key-latching bails to move all of said key-latching bails longitudinally at the same time to bring the lug formations on said key-latching bails into the narrow ends of the corresponding lug receiving apertures in said one frame plate, and spring means acting between said frame and said key-latching bails resiliently urging said key-latching bails to move longitudinally in a direction to bring the lug formations thereon into the wider ends of the corresponding lug receiving apertures in said one frame plate.

25 6. A calculating machine keyboard comprising a frame including spaced-apart and substantially parallel plates having key stem receiving apertures therein, digit keys disposed in ordinarily arranged rows and each having a flat stem extending slidably through said frame, each key stem having its major transverse dimension extending along the corresponding key row and having a latching detent projecting from one side thereof, key-latching bails extending one along each row of key stems between said plates and adapted to engage detent formations on key

30 stems in the corresponding rows to latch depressed keys in depressed position, spring means connected between said bails and said frame resiliently urging said bails in their key-latching direction, one of said frame plates having apertures therein tapering in width from one end to the other and each of said bails having a lug formation received in a corresponding tapered aperture in said one frame plate and effective when at the narrow end of the corresponding aperture to lock the associated key-latching bail in key-latching position and when at the wide end of the corresponding aperture to free the associated key-latching bail for movement out of key-latching position, "0" keys disposed one at one end of each row of digit keys and each having a stem extending slidably through said frame, means acting between each "0" key stem and the corresponding bail to move the bail longitudinally and bring the lug formation thereof into the narrow end of the corresponding lug receiving aperture in said one frame plate when the "0" key is manually raised, a rockable bail extending transversely of said frame and engaging said key-latching bails to move all of said key-latching bails longitudinally at the same time to bring the lug formations on said key-latching bails into the narrow ends of the corresponding lug receiving apertures in said one frame plate, and spring means acting between said frame and said key-latching bails resiliently urging said key-latching bails to move longitudinally in a direction to bring the lug formations thereon into the wider ends of the corresponding lug receiving apertures in said one frame plate.

35 7. A calculating machine keyboard comprising a frame including spaced-apart and substantially parallel plates having key stem receiving apertures therein, digit keys disposed in ordinarily arranged rows and each having a flat stem extending slidably through said frame, each key stem having its major transverse dimension extending along the corresponding key row and having a latching detent projecting from one side thereof, key-latching bails extending one along each row of key stems between said plates and adapted to engage detent formations on key

40 stems in the corresponding rows to latch depressed keys in depressed position, spring means connected between said bails and said frame resiliently urging said bails in their key-latching direction, one of said frame plates having apertures therein tapering in width from one end to the other and each of said bails having a lug formation received in a corresponding tapered aperture in said one frame plate and effective when at the narrow end of the corresponding aperture to lock the associated key-latching bail in key-latching position and when at the wide end of the corresponding aperture to free the associated key-latching bail for movement out of key-latching position, "0" keys disposed one at one end of each row of digit keys and each having a stem extending slidably through said frame, means acting between each "0" key stem and the corresponding bail to move the bail longitudinally and bring the lug formation thereof into the narrow end of the corresponding lug receiving aperture in said one frame plate when the "0" key is manually raised, a rockable bail extending transversely of said frame and engaging said key-latching bails to move all of said key-latching bails longitudinally at the same time to bring the lug formations on said key-latching bails into the narrow ends of the corresponding lug receiving apertures in said one frame plate, and spring means acting between said frame and said key-latching bails resiliently urging said key-latching bails to move longitudinally in a direction to bring the lug formations thereon into the wider ends of the corresponding lug receiving apertures in said one frame plate.

45 8. A calculating machine keyboard comprising a frame including spaced-apart and substantially parallel plates having key stem receiving apertures therein, digit keys disposed in ordinarily arranged rows and each having a flat stem extending slidably through said frame, each key stem having its major transverse dimension extending along the corresponding key row and having a latching detent projecting from one side thereof, key-latching bails extending one along each row of key stems between said plates and adapted to engage detent formations on key

50 stems in the corresponding rows to latch depressed keys in depressed position, spring means connected between said bails and said frame resiliently urging said bails in their key-latching direction, one of said frame plates having apertures therein tapering in width from one end to the other and each of said bails having a lug formation received in a corresponding tapered aperture in said one frame plate and effective when at the narrow end of the corresponding aperture to lock the associated key-latching bail in key-latching position and when at the wide end of the corresponding aperture to free the associated key-latching bail for movement out of key-latching position, "0" keys disposed one at one end of each row of digit keys and each having a stem extending slidably through said frame, means acting between each "0" key stem and the corresponding bail to move the bail longitudinally and bring the lug formation thereof into the narrow end of the corresponding lug receiving aperture in said one frame plate when the "0" key is manually raised, a rockable bail extending transversely of said frame and engaging said key-latching bails to move all of said key-latching bails longitudinally at the same time to bring the lug formations on said key-latching bails into the narrow ends of the corresponding lug receiving apertures in said one frame plate, and spring means acting between said frame and said key-latching bails resiliently urging said key-latching bails to move longitudinally in a direction to bring the lug formations thereon into the wider ends of the corresponding lug receiving apertures in said one frame plate.

55 9. In a calculating machine, a keyboard having a flat frame, ordinarily arranged rows of digit keys having flat stems extending slidably through said frame and each

stem having its major transverse dimension extending along the corresponding key row and having a detent formation projecting from one side thereof, rockable bails extending one along each key row and spring urged to engage the detent formations on the stems of depressed keys to latch the depressed keys in depressed position, means moving said bails against the force of said spring means to release depressed keys of said keyboard, selection bar actuating pins extending perpendicularly one from each key stem at one end of each stem, and guide plates extending one along each key row adjacent said frame and having guide notches therein individually receiving selecting bar actuating pins and holding said pins to straight line movements against the reaction between said pins and the selecting bars when the corresponding keys are depressed and released.

8. In a calculating machine, a keyboard having a flat frame, ordinally arranged rows of digit keys having flat stems extending slidably through said frame and each having its major transverse dimension extending along the corresponding key row and having a detent formation projecting from one side thereof, rockable bails extending one along each key row and spring urged to engage the detent formations on the stems of depressed keys to latch the depressed keys in depressed position, means moving said bails against the force of said spring means to release depressed keys of said keyboard, selecting bar actuating pins extending perpendicularly one from each key stem at one end of the key stem, and guide plates extending one along each key row adjacent said frame and having guide notches therein individually receiving said selecting bar actuating pins and holding said pins to straight line movements against the reaction between said pins and the selecting bars when the corresponding keys are depressed and released, said frame comprising flat plates secured in spaced-apart and parallel relationship to each other and having apertures therein loosely receiving said key stems.

9. A calculating machine keyboard comprising a flat frame, ordinally arranged rows of digit keys having flat stems extending slidably through said frame and each having its major transverse dimension extending along the corresponding key row and having a latching detent formation projecting from one side thereof, rockable key-latching bails extending one along each key row and spring

urged to key-latching position, and manually operated means carried by said keyboard and effective upon each row of digit keys individually to alternatively lock depressed digit keys in depressed position or to free depressed digit keys from said key-latching bails.

10. A calculating machine keyboard comprising a flat frame, ordinally arranged rows of digit keys having flat stems extending slidably through said frame and each having its major transverse dimension extending along the corresponding key row and having a latching detent formation projecting from one side thereof, rockable key-latching bails extending one along each key row and spring urged to key-latching position, and means engaging all of said key-latching bails and effective to simultaneously lock all of said key-latching bails in key-latching position.

11. A calculating machine keyboard comprising a flat frame, ordinally arranged rows of digit keys having flat stems extending slidably through said frame and each having its major transverse dimension extending along the corresponding key row and having a latching detent formation projecting from one side thereof, rockable key-latching bails extending one along each key row and spring urged to key-latching position, and means directly engaging all of said key-latching bails and effective to simultaneously move all of said key-latching bails to key-releasing position.

12. A calculating machine keyboard comprising a flat frame, ordinally arranged rows of digit keys having flat stems extending slidably through said frame and each having its major transverse dimension extending along the correspondingly key row and having a latching detent formation projecting from one side thereof, rockable key-latching bails extending one along each key row and spring urged to key-latching position, means engaging all of said bails and effective to simultaneously lock all of said key-latching bails in key-latching position, and means engaging all of said key-latching bails and effective to simultaneously move all of said key-latching bails to key-releasing position.
